UNITED STATES PATENT OFFICE.

HERBERT A. YEARICK, OF SUNBURY, PENNSYLVANIA.

ELECTRICAL SWITCH.

1,207,260.

Specification of Letters Patent.

Patented Dec. 5, 1916.

Application filed February 2, 1916. Serial No. 75,799.

To all whom it may concern:

Be it known that I, HERBERT A. YEARICK, a citizen of the United States, residing at Sunbury, in the county of Northumberland and State of Pennsylvania, have invented certain new and useful Improvements in Electrical Switches, of which the following is a specification, reference being had to the accompanying drawings.

10 This invention relates to certain improvements in electrical switches and it is an object of the invention to provide a device of this general character having novel and improved means whereby the same is conveniently and effectively cooled and is an improvement on the device disclosed in Patent No. 1,185,749, dated June 6, 1916.

Furthermore it is an object of my invention to provide a novel and improved switch 20 wherein the operating means for the blade or blades may be readily applied to or removed from operative assemblage.

The invention also contemplates for an object to provide a novel and improved 25 switch wherein the switch blade or blades and the coacting contact lugs or jaws depend from a frame removably mounted upon a cooling member and into the chamber of which the same extend.

30 A still further object of the invention is to provide a switch of this general character having novel and improved means whereby the same may be air cooled and wherein the entrances for the air are protected in such 35 a manner as to reduce to a minimum the possibility of passage through the opening of foreign matter which would interfere with or obstruct the operation of the switch.

The invention consists in the details of 40 construction and in the combination and arrangement of the several parts of my improved switch whereby certain important advantages are attained and the device is rendered simpler, less expensive and otherwise 45 more convenient and advantageous for use, all as will be hereinafter more fully set forth.

The novel features of the invention will hereinafter be definitely claimed.

50 In order that my invention may be the better understood, I will now proceed to describe the same with reference to the accompanying drawings, wherein—

Figure 1 is a longitudinal vertical sec-

tional view taken through an electric switch 55 constructed in accordance with an embodiment of my invention: Fig. 2 is a view partly in top plan and partly in section of the device as disclosed in Fig. 1; Fig. 3 is a transverse vertical sectional view taken 60 through the device as herein embodied, and at one side of its longitudinal center; Fig. 4 is a fragmentary diagrammatic view illustrating certain features of the invention as 65 herein embodied; and Fig. 5 is a fragmentary detail view illustrating one of the bearings for the operating shaft as herein disclosed.

As disclosed in the accompanying drawings, 1 denotes a receptacle of predetermined 70 dimensions and preferably rectangular in plan with its top face open and the interior thereof affording a cooling chamber *a*, and as herein embodied, the side walls and bottom of said container are provided with the 75 openings 2 of predetermined diameter and which have disposed across their inner ends the shields 3, each of said shields having its intermediate portion offset and its extremities secured to the adjacent faces of 80 the walls or sides of the receptacle, whereby it will be perceived that the possibility of foreign substances passing within the chamber *a* through said openings 2 is substantially eliminated.

85 Resting upon the free edges of the side walls of the container is the frame F of a configuration similar to that of the container 1 and provided at its inner longitudinal margins relative to the container 1, with the inturned flanges 4 and having its end walls provided with the outstanding lugs 5 provided with the open slots 6 adapted to receive the threaded shanks 7 pivotally engaged with the end walls of the container 1, said shanks 7 having coacting therewith the conventional clamping nuts 8 coacting with the lugs 5 in a well known manner in order to effectively and conveniently clamp the frame F to the container 1, yet at the same time permit its ready removal when the necessities of practice may so require. The inturned flanges 4 serve as a support for the table or plate 9 produced of suitable non-conductive material and 90 preferably asbestos wood and depending from said table or plate 9 relative to the container 1 are the frames 11 arranged at

opposite sides of the transverse center of the table or plate 9 and to which the contact jaws or lugs 12 are suitably anchored. Intermediate the frames 11, the table or plate 9 has disposed therethrough the binding posts 14 from which a suitable conductor is operatively engaged adapted to lead to a motor, while the lugs or jaws 12 are in proper electrical connection with a suitable source of electrical energy through the medium of the conductors B connected with the binding post 15 disposed through the table or plate 9 and electrically connected with the lugs or jaws 12 through the medium of the metallic plates 16.

As herein embodied, my improved switch is of a three-phase type and as the wiring or electrical connections are conventional, it is thought that a detail description thereof is unnecessary.

Each of the binding posts 14 has the pivotally mounted switch plate 18 adapted to coact with a contact jaw or lug 12 at opposite sides of the intermediate binding post 14 with which the same coacts, whereby it will be perceived that when the blade is substantially vertical, the switch is neutral and that when it coacts with one of the jaws or lugs 12, the motor will be caused to run in one direction and when coacting with the second lug or jaw 12, the motor will be caused to run in an opposite direction, as is well known. As herein set forth, the free extremities of the blades 18 are connected to the bar 19 formed of suitable non-conductive material, preferably wood asbestos board, whereby it will be perceived that the blades 18 will be caused to move in unison and in the same general direction. The opposite extremities of the bar or rod 19 are positioned within the longitudinally disposed slots 20 formed in the lower extremities of the levers 21 fixed to a shaft 22 disposed transversely of the frame F at substantially its longitudinal center and at a point in alignment with the binding posts 14 hereinbefore referred to, said shaft 22 being rotatably mounted in the recesses 23 formed in the outer longitudinal edges of the frame F and also within the recesses 24 formed in the flanges 25 of the closure member or lid 26, which is adapted to close the outer face of the frame F. It is to be observed that the longitudinal margins of the table or plate 9 and the adjacent portions of the longitudinally disposed flanges 4 are cut away, as indicated at 27, in order to afford no obstruction to the movement of the levers 21.

An end portion of the shaft 22 extends exteriorly of the frame F and has secured thereto the operating lever 28 adapted to be operated in any preferred manner, and whereby it will be perceived that the requisite movement will be imparted to the blades 18.

It is to be observed that the ends of the closure member or lid 26 extend beyond the ends of the frame F and are provided with the open slots 29 to receive the threaded shanks 30 pivotally engaged with the ends 70 of the frame F and with which coact the conventional winged nuts 31 to effectively clamp the closure member or lid 26 in applied position, or permit said lid or closure member 26 to be readily removed when the necessities of practice so require.

While I have hereinbefore described my improved switch as being air cooled, it will be understood that by sealing the openings 2 in the container 1, said container may be properly filled with a supply of oil. As this construction and arrangement is obvious, it is thought that an illustration thereof is unnecessary.

While I have disclosed my switch as a three-phase switch, it is to be understood that I do not limit myself to this particular form, as it will be at once perceived that my invention may be employed in connection with any switch of a knife or blade type.

From the foregoing description, it is thought to be obvious that a switch constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A switch of the character described comprising a container with one face open, a frame detachably engaged with the open-face portion of the container and having its engaging end and the opposite end open, a closure member for the outer end of the frame detachably engaged with the frame, said closure member being provided with inturned flanges directly engageable with the outer end of the frame, said flanges and frame being provided with registering recesses, stationary contacts carried by the frame and extending within the container, switch blades pivotally supported by the frame and coacting with the stationary contacts, a member connecting said blades whereby the same are caused to move in unison and in the same general direction, a shaft rotatably supported by the frame and extending through the registering recesses of the frame and closure member whereby said shaft may be readily removed upon removal of the closure member, means for

rocking the shaft, and a lever fixed to the shaft and extending within the container and having its free end provided with an open slot to receive the connecting member for the blades whereby said lever may be readily disengaged from the connecting member upon removal of the shaft.

In testimony whereof I hereunto affix my signature in the presence of two witnesses:

HERBERT A. YEARICK.

Witnesses:

F. R. MORRIS,
BONNELL N. CLARK.
